UNITED STATES PATENT OFFICE

2,307,324

DRAINAGE APPARATUS

Donald E. Larson, Chicago, Ill., assignor to Chicago Bridge & Iron Company, a corporation of Illinois

Application January 22, 1942, Serial No. 427,821

3 Claims. (Cl. 137—20)

This invention relates to improvements in drainage apparatus and more especially such apparatus for draining rain water from a concave roof or a roof having a concavity therein. The invention is applicable, for example, in connection with the drainage of concave roofs of oil storage tanks and the like.

Some storage tanks of this character are made with roofs that rise and fall with changes in internal pressure so that at times the center of the roof is in a lower position than the periphery, thus forming a concavity that collects rain water unless suitable drainage means is provided.

Heretofore difficulty has been encountered in draining such concave roofs. It has been customary to provide a flexible drain pipe through the tank but this has proved objectionable because of the difficulty in obtaining access thereto. There are also other objections to draining the water from the roof of a tank down through the tank.

Among the features of my invention is the provision of drainage apparatus that is entirely outside of the tank. I have here illustrated the invention in use on a cylindrical tank having a concave roof.

In general, my improved apparatus comprises a siphon drain pipe with its upper leg connected to the concavity in the roof to be drained and its lower leg leading to a point outside of the tank below the roof. I provide means exposed to falling rain adapted to direct rain water into the lower leg of the siphon to start the same. In a device of this kind the low point or sump may be a relatively great distance from the periphery of the roof which is usually the high point. Consequently, the upper leg of the siphon may be of considerable length. In a case of this kind, therefore, it may be necessary or advisable to provide a relatively great amount of water in the lower leg in order to insure starting of the siphon. Consequently, I provide means for temporarily retaining a predetermined minimum amount of water in the lower leg before starting the siphon and then discharging the same to start the siphon. I accomplish this by yieldingly closing the lower leg with means adapted to be opened by a predetermined amount of water in the lower leg.

Other features and advantages of my invention will appear more fully as I proceed with my specification.

In those forms of device embodying the features of my invention illustrated in the accompanying drawings, Fig. 1 is a view in side elevation, Fig. 2 is a view taken as indicated by the

line 2 of Fig. 1, Figs. 3, 4, 5 and 6 are diagrammatic views showing the operation of the device, Fig. 7 is a view similar to Fig. 2 showing a modified form, Fig. 8 is an enlarged fragmentary view of the lower end of the lower leg of the siphon, and Fig. 9 is an enlarged sectional view of the swivel joint in the outlet pipe.

As shown in the drawings, 10 indicates a cylindrical tank with a concave roof 11 having a central sump 12. 13 indicates in general the upper leg of a siphon drain pipe and 14 the lower leg thereof. The end 13a of the upper leg 13 has its end in the sump 12.

The lower end of the lower leg 14 is enlarged as indicated by 14a to provide a vacuum chamber. This is designed to give enough capacity to the lower end of the lower leg of the siphon so that after the siphon starts there will be enough discharge to completely fill the upper leg 13 and thus insure continuous operation of the siphon after the start until the roof is entirely drained.

The lower end of the vacuum chamber 14a is provided with a swivel discharge pipe 15 having an enlarged end 15a. This pipe is normally held in a substantially upright position as shown in Figs. 1 and 2 by the counter-weight 16. It is swiveled to the outlet pipe 14b at the bottom of the vacuum chamber by the swivel joint 17. See Fig. 9.

30 The lower end of the vacuum chamber 14a is connected by the pipe 18 to a trough 19 attached to the wall of the tank on the outside at a level somewhat above the top of the vacuum chamber 14a. This trough should be long enough so that 35 whenever a rain starts it will quickly collect enough water to substantially fill the vacuum chamber 14a. I have here shown this trough as extending entirely around the tank 10.

Rain water running down the shell 10 is caught 40 in the trough 19 and then flows into the vacuum chamber 14a. As the vacuum chamber becomes almost full, the weight of water in the enlarged end 15a of the swivel discharge pipe causes it to descend as shown by the arrows in Figs. 4 and 5.

45 When it is down as shown in Figs. 5 and 6, water flows out of the discharge spout 15b thus draining the vacuum chamber 14a and starting the siphon. Flow through the siphon continues until the roof is drained. As the enlarged end 15a of the discharge pipe becomes nearly empty as shown in Fig. 6, the weight of the counterweight 16 causes it to rise to an upright position as indicated by the arrow in Fig. 6, the discharge pipe normally remaining in an upright position as shown in Fig. 3 until the next rain fall.

Instead of providing a trough 19 on the shell of the tank on the outside, I may provide a trough at the periphery of the roof as shown in Fig. 7, by sloping the outer margin of the roof downwardly slightly as indicated by 111a and providing a periphery flange 119. The trough thus formed is connected to the vacuum chamber 114a by the pipe 118 which corresponds to the pipe 18 in the other figures. In other respects the general construction and operation of the device of Fig. 7 is the same as that of Figs. 1 and 2, the swivel discharge pipe 115 with its enlarged end 115a and its counterweight 116 corresponding to parts 15, 15a and 16, respectively, of the device of Figs. 1 and 2.

While I have shown and described certain embodiments of my invention, it is to be understood that it is capable of many modifications. Changes, therefore, in the construction and arrangement may be made without departing from the spirit and scope of the invention as disclosed in the appended claims, in which it is my intention to claim all novelty inherent in my invention as broadly as permissible, in view of the prior art.

What I claim as new, and desire to secure by Letters Patent, is:

1. Drainage apparatus for a concave roof, including: a syphon drain pipe with its upper leg connected to the concavity in the roof to be drained and its lower leg leading to a point below the roof; means exposed to falling rain adapted to direct rain water into the lower leg of the syphon to start the same; and means for yield-

ingly closing the lower leg, said means adapted to be opened by a predetermined minimum amount of water in the lower leg.

2. Drainage apparatus for a concave roof, including: a syphon drain pipe with its upper leg connected to the concavity in the roof to be drained and its lower leg leading to a point below the roof; means exposed to falling rain adapted to direct rain water into the lower leg of the syphon to start the same; an enlargement with a discharge opening at the lower end of the lower leg; and means for yieldingly closing said discharge opening, said means adapted to be opened by a predetermined minimum amount of water in said enlargement.

3. Drainage apparatus for a concave roof, including: a syphon drain pipe with its upper leg connected to the concavity in the roof to be drained and its lower leg leading to a point below the roof; means exposed to falling rain adapted to direct rain water into the lower leg of the syphon to start the same; a swivel discharge pipe at the lower end of the lower leg; and means for yieldingly holding said discharge pipe in a substantially upright position, whereby a predetermined minimum amount of water will temporarily be trapped in the lower end of said lower leg and in said discharge pipe, the weight of water in said discharge pipe exceeding said predetermined minimum amount, adapted to lower said discharge pipe to permit discharge of water therethrough from said lower leg.

DONALD E. LARSON.
